[57] **CLAIM**

The ornamental design for a bottle holder, as shown and described.

DESCRIPTION

FIG. 1 is a side elevational view of a bottle holder showing our new design; the other three sides are identical therewith. The broken line showing of a bottle is for illustrative purposes only.

FIG. 2 is a top plan view thereof; and

FIG. 3 is a bottom plan view thereof.

FIG. 1

FIG. 2

FIG. 3
